UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

COIN-GAGE FOR TELEPHONE PAY-STATIONS.

1,188,666.

Specification of Letters Patent. Patented June 27, 1916.

Application filed March 13, 1916. Serial No. 83,785.

To all whom it may concern:

Be it known that I, GEORGE A. LONG, a citizen of the United States, residing at Hartford, in the county of Hartford and 5 State of Connecticut, have invented certain new and useful Improvements in Coin-Gages for Telephone Pay-Stations, of which the following is a specification.

This invention relates to what I shall for 10 convenience term a "coin-gage" for telephone pay-stations.

As will be inferred it is conceivable that the device can be used in several connections, although it is primarily intended for association with, or as part of the equipment of, 15 a telephone pay-station. An article of the latter character, generally comprises a box or casing surmounted by what is known as a "coin-gage" which has an opening or hole 20 or several thereof, for the reception of the necessary coin or coins, which after it or they leave the gage passes or pass into the box.

Coin gages as now made are so far as I 25 am aware, cast, consisting usually of two sections united by rivets, screws or otherwise. A cast coin gage is an expensive article to produce, requiring many and widely-different operations in its production. I 30 provide a coin gage which is susceptible of ready and inexpensive manufacture, and although comparatively light possesses the requisite strength. The coin gage can, as will be obvious, receive but a single coin or 35 can be organized to receive coins of different denominations, there being in the latter case preferably several openings or holes through which the coins are passed.

While as I observe the device is of especial 40 utility when employed in conjunction with a telephone pay-station, it can be used with equal advantage in other fields, for which reason the title selected has been adopted.

45 In the drawings accompanying and forming part of the present specification I have shown in detail one convenient form or embodiment of the invention which to enable those skilled in the art to practice the same 50 will be set forth fully in the following description. I do not limit myself to this exact disclosure; I may depart therefrom in several respects within the scope of the invention defined by the claims following said 55 description.

Referring to said drawings: Figure 1 is a front elevation, and Fig. 2 a rear elevation of a coin-gage involving the invention. Fig. 3 is an inside face view of the front section, and Fig. 4 a like view of the back section. Fig. 5 is a longitudinal section on the line 5—5 of Fig. 1, looking in the direction of the arrow. Fig. 6 is an end view as seen from the right in Fig. 1 with the two sections separated. Figs. 7, 8 and 9 are cross sections on the lines 7—7, 8—8 and 9—9 respectively of Fig. 1, looking in the direction of the arrows.

Like characters refer to like parts throughout the several views.

As already stated coin gages now in use are cast. Mine is made from sheet metal. It can be cut from suitable stock and stamped up with the aid of the necessary dies and punch presses. As shown (Fig. 6) 75 the article comprises a back section as 2 and a front section as 3. I will hereinafter describe how these sections can be associated. If necessary they may be rigidly connected together by spot-welding, riveting or otherwise. There may be instances where they can be rigidly held in proper relation with each other by a simple fit or interlocking. The back section 2 has a rearwardly extending foot 4, while the front section has a forwardly extending foot 5, the two feet (Figs. 6 to 9) being in alinement and constituting a suitable base. When the device is used in connection with a telephone pay station these feet 4 and 5 are horizontally disposed, 80 rest on the top of the pay-station box and are secured thereto in some suitable manner as by screws (not shown) extending through perforations 6 in the feet.

In elevation both sections 2 and 3 (Figs. 95 1 to 4) are practically of similar shape, although as represented the area or superficial extent of the front section 3 is a little greater than that of the rear section 2. The upper and lower edges of the sections are straight 100 and practically in parallelism, while the ends thereof converge on similar angles toward the tops of the sections. Along the ends and top of the front section 3 is a flange 7 shown as extending rearwardly therefrom 105 and as unbroken or continuous from end to end thereof, this flange being adapted to receive within it (Fig. 5) the back section 2. The front section 3 as illustrated has three holes 8, 9 and 10, circular in form and of a 110

diameter or size to freely receive twenty-five, ten and five-cent pieces respectively. Extending inwardly or rearwardly from the intermediate portion of said section 3 is an annular flange 11, the inner face of which is flush or coincident with the wall of the hole 9, while projecting inwardly from said section 3 near one end thereof is the annular flange or lip 12, the inner surface of which is flush with the wall of the hole 10. The two annular or circular flanges 11 and 12 are not as deep as the marginal flange 7, as will be seen on reference to Fig. 5 for a reason that will hereinafter appear.

The back section 2 has near one end (the left as shown in Fig. 4) the forwardly-projecting portion 13, the front of which is practically flat and sides of which converge upward into a rounded top or crown. Extending from the apex of the forward projection 13 is the flange 14 which extends unbrokenly from the apex of said portion 13 to the end of the section 2 opposite that provided with said projecting portion 13.

As seen in Fig. 5 the section 2 is received within the section 3, the end and top portions of the flange 7 overlying the said rear section 2. With this relation the two relatively interfitted parts can be connected together if desired at proper intervals by spot-welding or riveting or the section 2 may be driven into the section 3. In the latter event the sections would be held interlocked together by a "fit" as it is known.

When the two sections are operatively assembled the edge of the flange 14 abuts against the front section 3. On the lower inner side of the forwardly projecting portion 13 is a practically vertically-disposed projecting or wedge-shaped portion 15, while between said wedge-shaped portion 15 is a second projecting or wedge-shaped portion 16, the latter being situated at a slight slant and between the portion 15 and the downturned end of the flange 14. The left side of the wedge-shaped projection 15 and the adjacent part of the flange 7 present a runway for twenty-five cent pieces, the distance between the outer face of said wedge-shaped portion and adjacent part of the flange 7 equaling practically the diameter of such coin. The distance between the two wedge-shaped portions 15 and 16 practically equals the diameter of the ten-cent piece, while the distance between the portions 16 and the adjacent part of the flange 14 constitutes a runway for five-cent pieces, being spaced intervals respectively necessary to receive such coins. It will be perceived that the inner edges of the flanges 11 and 12 are spaced from the adjacent face of the section 2, the interval being enough to receive flatwise ten-cent and five-cent pieces respectively. It will be also noted that the hole 8 is plain or non-flanged, the surface

of the plate or section 3 adjacent the twenty-five cent opening being spaced from the front face of the forwardly deflected portion 13 a distance equal to the thickness of a quarter, so that after such coin has passed through the opening 8 it can descend along the runway presented jointly by the wedge portion 15 and the adjacent part of the flange 7.

While as will be clear there are advantages following the construction of the gage from sheet metal, there may be instances where one or even both parts might be cast or otherwise made.

What I claim is:

1. A coin gage comprising sections, one of which has a hole for a coin, the two sections being connected together and the section which has the hole being provided with an annular flange, the inner surface of which is flush with said hole and the inner edge of which is spaced from the companion section a distance approximately equal to the thickness of the coin which is to pass through said hole.

2. A coin gage comprising a back section and a front section rigidly united to each other, the back section being provided on its inner lower side with a projecting portion, said back section being provided with a second projecting portion between said other projecting portion and the other end of said rear section to thus present on the inner face of said back section a plurality of runways, the front section having coin holes coincident with the several runways.

3. A coin gage comprising a back section and a front section, the front section having a rearwardly extending marginal flange, the rear section being confined within said flange and having at one end a forward projection, said rear section also having a flange extending along the margin thereof from the upper end of said projection to the other end of said rear section, said rear section also having wedge shaped portions on the inner side thereof, one on said projection and the other between said projection and the adjacent end of the flange of said rear section to thus present coin runways, the front section having coin receiving holes in register with said runways, said front section also having annular flanges, the inner faces of which are respectively flush with the walls of two of the holes and the edges of which are separated from the rear section, that part of the front section which has the other hole being spaced from said projection.

4. A coin gage comprising a back section and a front section, the front section having a rearwardly extending marginal flange, the rear section being confined within said flange and having at one end a for-

ward projection, said rear section also having a flange extending along the margin thereof from the upper end of said projection to the other end of said rear section, 5 the latter also having wedge-shaped portions on the inner side thereof, one on said projection and the other between said projection and the adjacent end of the flange of said rear section to thus present coin

runways, the front section having coin-re- 10 ceiving holes in register with said runways.

In testimony whereof I affix my signature in presence of two witnesses.

GEORGE A. LONG.
